TWIN DRAFT-GEAR.

1,107,275.

Specification of Letters Patent. Patented Aug. 18, 1914.

Application filed March 1, 1912. Serial No. 680,864.

To all whom it may concern:

Be it known that I, CLYDE C. FARMER, a citizen of the United States, residing at Chicago, in the county of Cook and State 5 of Illinois, have invented new and useful Improvements in Twin Draft-Gear, of which the following is a specification.

This invention relates to draft gear for railway cars, and more particularly to a 10 draft gear attachment for a twin draft gear installation.

In heavy railway service, particularly on large locomotives, it has been proposed to employ two draft gear units in place of 15 one heretofore employed, in order to increase the capacity of the draft gear to resist shocks due to buffing and draft movements. These draft gear units are mounted side by side and it has been found in practice 20 that where the usual form of follower plate is employed, there is liable to be an uneven or non-uniform compression of the draft gears due to the difficulty of providing two gears each having the same compressive resistance.

The principal object of my invention is to provide a twin draft gear attachment having means for insuring a uniform compressive movement of the draft gear units 25 under buffing and draft stresses.

Other objects and advantages will appear in the following more detailed description of a construction embodying my invention.

In the accompanying drawing, Figure 1 35 is a vertical longitudinal section of a twin draft gear installation embodying my improvement, the section being taken on the line B—B of Fig. 2; Fig. 2 a plan view thereof, partly in section; Fig. 3 a transverse section thereof on the line A—A of Fig. 1; Fig. 4 an isometric projection of the rear follower plate; Fig. 5 an isometric projection of the front follower plate; and Fig. 6 an inverted isometric projection of 40 the front follower plate.

As shown in the drawing, a draft gear casing 1, preferably a steel casting, is suitably secured to and between the usual car center sills 2. Said casing has a continuous 45 top forming a roof over the draft gears, but the lower side is open to permit the installation and removal of the draft gear parts. Mounted within the casing 1 are follower plates 3 and 4, the rear follower plate 3 having side walls 5, a top wall 6,

and a rear wall 7 and the front follower plate 4, having side walls 9, a lower wall 10, and a front wall 11. The side walls of the follower plates are partly cut away, as shown, to permit the side walls of one follower plate to rest in the spaces thereby formed in the side walls of the other follower plate.

Within the box-like space formed by the front and rear follower plates are mounted the draft gear units, such as the friction draft gears 12 and 13. The follower plates and the draft gear units are supported in position by means of straps 14 suitably secured at the front and rear portions to the 65 casing 1, the front follower plate 4 being adapted to rest on said straps. The usual yoke 8 is preferably arranged intermediate of the draft gears 12 and 13 and may be secured in the usual manner to the draw-bar 15. The front follower plate 4 is preferably provided on its front wall 11 with a concave surface 16 forming a rocker bearing for a convex shaped projection 17 on a block 18 carried by the draw-bar 15 and the rear follower plate 3 is provided with a similar concave surface 19 forming a rocker bearing for a convex shaped projection 20 in the interior of the rear end of the yoke 8. The front follower plate 4 bears against stop members 21 formed on the casing 1 while the rear follower plate 3 bears against stop members 22 also formed on the casing 1.

When the draft gear is not under stress the parts are disposed as shown more clearly in Fig. 1, with the front and rear follower plates in engagement respectively with the front and rear ends of the draft gear units 12 and 13. It will be noted that a certain 90 space exists between the front wall 11 of the follower plate 4 and the wall 6 of follower plate 3 and a similar space is provided between the rear wall 7 of the follower plate 3 and the wall 10 of the follower plate 4. These spaces permit of relative longitudinal movement of the follower plates and are limited in extent to an amount slightly less than the movement necessary to compress the draft gear solid. In this manner the draft gear units are protected from excessive 95 shocks and any stresses in excess of the capacity of the gears are transmitted through the follower plates directly to the casing 1. The side walls of the follower plates are 100 105 110

adapted to bear against the inner faces of the casing 1 when the draft gear is in action, and in order to eliminate as much friction as possible, the inner walls of the casing 1 may be provided with projecting bearing faces 23 to form guide surfaces for the follower plates.

In operation, upon the application of a buffing stress, the front follower plate 4 is moved rearwardly away from the stops 21 by the draw-bar 15, compressing the draft gear units, and if it should happen that one draft gear unit offers less resistance to movement than the other, the more rapid compression of that gear will be prevented by the engagement of the side walls of the follower plates with the casing, which necessitates the substantially uniform and parallel movement of the follower plates and consequently a corresponding movement of the draft gear units. If the buffing stress should exceed the capacity of the draft gear units, the front and rear follower plates come together and close the spaces between the longitudinal walls and the end walls just before the gears are compressed solid, thereby causing the transmission of the excessive stress from the draw-bar through the follower plates directly to the draft gear casing and consequently the draft gears are protected from damage.

It will be noted that the construction of

the follower plates is such that the front follower plate forms a cradle or carrier plate for supporting the draft gears while the space left between the plates on the under side and at the rear permits of the ready inspection of the friction strips and the preliminary springs of the friction draft gears.

Having now described my invention, what I claim as new and desire to secure by Letters Patent, is:—

In a draft gear mechanism, the combination with a draw-bar, of draft gear units mounted side-by-side and follower plates for said draft gear units, one provided with a flat horizontal member constituting the sole support for the draft gear units and having vertical side walls forming a channel with the horizontal member and a transverse end member for engaging the draft gear units at one end and the other follower plate having an upper horizontal member covering the draft gear units, vertical side walls adapted to engage the side walls of the first follower plate, and a transverse plate at one end for engaging the opposite ends of the draft gear units.

In testimony whereof I have hereunto set my hand.

CLYDE C. FARMER.
